Primary Examiner — George D. Kirschbaum*Assistant Examiner* — Lillian Windham(74) *Attorney, Agent, or Firm* — Knobbe, Martens, Olson & Bear, LLP.(57) **CLAIM**

The ornamental design for a wearable temperature measurement device, as shown and described.

DESCRIPTION

FIG. 1 is a perspective view of a wearable temperature measurement device embodying our new design;

FIG. 2 is top view thereof;

FIG. 3 is bottom view thereof;

FIG. 4 is a front view thereof;

FIG. 5 is a back side view thereof;

FIG. 6 is a right side view thereof; and,

FIG. 7 is a left side view thereof.

Broken lines, where shown, are used to illustrate portions of the wearable temperature measurement device that form no part of the claimed design.
